UNITED STATES PATENT OFFICE.

NICHOLAS POTTER, OF TROY, PENNSYLVANIA.

CORN-SHELLER.

SPECIFICATION forming part of Letters Patent No. 313,619, dated March 10, 1885.

Application filed October 10, 1884. (No model.)

To all whom it may concern:

Be it known that I, NICHOLAS POTTER, of 5 Troy, in the county of Bradford and State of Pennsylvania, have invented a new and useful Improvement in Corn-Shellers, of which the following is a full, clear, and exact description.

Reference is to be had to the accompanying drawings, forming a part of this specification, 10 in which similar letters of reference indicate corresponding parts in all the figures.

Figure 1 is a side elevation of one of my improved corn-shellers. Fig. 2 is a sectional end elevation of the same, taken through the line 15 $x x$, Fig. 1. Fig. 3 is a sectional plan view of the same, part being broken away.

The object of this invention is to promote convenience and economy in the construction of corn-shellers.

2) The invention consists in the construction and combination of parts, as will be first described, and then specifically pointed out in the claims.

3) A are the side boards of the shell or casing, 25 which are made of any suitable length, breadth, and thickness, and are secured by bolts B to the side edges of the end boards, C.

To the upper edges of the side and end boards, A C, is secured the top board, D, by 30 screws E.

To and between the lower parts of the side boards, A, are secured, by screws F, the inclined boards G, that form a spout or chute to conduct the shelled corn from the machine.

35 To the end parts of the side boards, A, are secured, by the bolts B, the upper parts of the bars H, of iron or other suitable material, the lower parts of which serve as legs, and are made of such a length as to raise the machine 40 to a suitable height. The lower parts of the bars H are inclined outward, as shown in Fig. 2, to obtain such a width of base as will give the machine a firm and stable support.

I is the shelling-wheel, which has teeth up- 45 on its inner side to remove the kernels from the ears, and J is the feed-wheel, the rim of which is beveled and is corrugated or roughened to take hold of the ears and feed them downward along the toothed side of the shell- 50 ing-wheel I. The shelling-wheel I is attached to a shaft, K, and has a large gear-wheel, L,

and a small gear-wheel, M, formed upon its outer side. The teeth of the small gear-wheel M mesh into the teeth of the gear-wheel N, attached to the shaft O, one end of which projects to receive a crank or pulley for applying power to the machine. The teeth of the large gear-wheel L mesh into the teeth of the small gear-wheel P, attached to the shaft Q, to which the feed-wheel J is attached. The end of the 60 shaft Q, upon the opposite side of the machine from the projecting end of the shaft O, projects to receive a crank or pulley for applying power to the machine. By this means the machine may be operated by two persons from 65 its opposite sides or from one side only.

The bearings R S T upon one side and the bearings R T upon the other side of the machine, in which the shafts K O Q, respectively, revolve, are formed each in one piece, which 7c pieces are securely bolted to the side boards, A, by which construction the said bearings will be less expensive in manufacture and will give greater firmness and strength to the machine than where separate bearings are used. 75 I do not claim this construction of bearing, however, as of my invention. The ears are held against the wheels I J while passing through the machine and being shelled by an arm, U, formed upon or attached to the inner 80 end of the short shaft V, which rocks in a bearing, W, secured in an aperture in one of the side boards, A. The shaft V and bearing W are placed in a laterally-inclined position, as shown in Fig. 3, so that the arm U will press 85 the ear into and hold it in the angular space between the wheels I J while being shelled.

To the outer end of the inclined shaft V is secured, by a set-screw or other suitable means, the end of a lever, X, which is bent into a position parallel with the side board, A, and which has a number of holes formed in it to receive a hook, Y, attached to the weight Z, so that the said weight can be adjusted at a greater or less distance from the shaft V, as 95 may be required. The downward movement of the free end of the arm X is limited by a bracket, a, or other stop, attached to the side board, A, and the weight Z is kept from swinging outward by a keeper, b, attached to the 100 said side board, A, and through which the hook Y or weight Z passes. The weight Z may, if

desired, be replaced by a spring. The ears are introduced through a hopper, *c*, secured in an aperture in the top board, *D*. The shelled corn escapes through apertures in the grate *d*, secured to the side board, *A*, and between the edge of the said grate and the shelling-wheel *I*. The cobs are forced out by the shelling-wheel *I* through an aperture in the upper part of the rear end board, *C*, and are kept from being carried too high by a guard-plate, *e*, attached to the front side board, *A*.

f are guard-plates attached to the casing to protect the gearing from being impeded by kernels of corn.

Having thus described my invention, I claim as new and desire to secure by Letters Patent—

1. A corn-sheller of the character described, consisting, essentially, in the frame, the shafts *K O Q*, journaled in the sides of the frame, the shelling-wheel *I*, inside of the frame secured

to the shaft *K* and formed with peripheral teeth *L*, the shelling-teeth on its inner face and the small gear *M* on its outer face, the pinion *N*, secured to the inner end of shaft *O* and meshing with the gear *M*, the pinion *P*, on shaft *Q*, meshing with the teeth *L*, the feed-wheel *J*, on the shaft *Q* within the frame and having inclined peripheral teeth, and a weighted holding-arm, substantially as set forth. 25

2. In a corn-sheller of the character described, the combination, with the shelling and feed wheels, of the pivoted holding-arm *U*, its shaft *V*, the lever *X*, having a series of perforations, the weight *Z*, having a hook, *Y*, the guide *b*, and the stop *a*, substantially as set forth. 30

NICHOLAS POTTER.
